(No Model.)

J. W. MORRISON.

MACHINE FOR WETTING PAPER.

No. 289,688.

Patented Dec. 4, 1883.

UNITED STATES PATENT OFFICE.

JOHN WESLEY MORRISON, OF OMAHA, NEBRASKA.

MACHINE FOR WETTING PAPER.

SPECIFICATION forming part of Letters Patent No. 289,688, dated December 4, 1883.

Application filed March 14, 1883. (No model.)

To all whom it may concern:

Be it known that I, JOHN W. MORRISON, of Omaha, in the county of Douglas and State of Nebraska, have invented ^{and} Improved 5 Machine for Wetting Paper, of which the following is a full, clear, and exact description.

My improvements relate to machines for wetting paper in quires or quantity preparatory to printing; and the invention consists in 10 certain novel features of construction and arrangement, having the object to place the work entirely under control of the operator, and also to facilitate the work, as hereinafter described and claimed.

Reference is to be had to the accompanying drawings, forming a part of this specification, in which similar letters of reference indicate corresponding parts in all the figures.

Figure 1 is a side elevation of the machine. 2c Fig. 2 is a vertical longitudinal section. Fig. 3 is an end elevation of the machine. Figs. 4 and 5 are detail views of the cam and clutch mechanism.

A is a tank for containing water, supported 25 at a suitable height on standards *a a*.

b b are feed-rollers supported across one end or side of the tank by suitable bearings on standards *a*, the boxes *b'* of the upper roller being fitted to slide, and held down by springs.

30 *c c* are the discharge-rollers, similarly fitted at the opposite end or side of the tank, the upper roller *c* having a sliding bearing, *c'*.

Each pair of rollers *b b* and *c c* are geared together. The lower roller *b* is rotated by 35 gearing direct from a gear-wheel, *d*, on the main shaft *e*, and the lower roller *c* by a shaft, *d'*, connected by beveled gears *c'* to said roller, and connected at its other end by a bevel-pinion, *e'*, to bevel-cogs on the side of wheel *d*.

40 *f f' f'* are guide-rollers within the tank, for endless cords or belts *g*, that pass, one set from upper roller *b* to upper roller *c*, and the other cords from lower roller *b* to lower roller *c*, both sets of cords passing over rollers *f'* and beneath 45 roller *f*, which is lowest in the tank, but always above the water-level.

g' g' are rollers at the bottom of the tank, for retaining the under side of the lower cords out of the way.

50 *h* is a pan, preferably of concave form, hung

beneath roller *f*, on the end of a lever, *i*, that is fulcrumed on a post, *h'*.

i is a hinged flap-valve in the bottom of the pan, opening upward to allow the pan to fill as it drops in the water. 55

k is a rod connected to the end of lever *i*, that extends outside the tank, and extending to shaft *e*, where the end of rod *k* is slotted to stride the shaft. 60

l is a cam loose on shaft *e*. 60

l' is a pin on rod *k*, extending over the cam, as shown in Fig. 4.

m is a sliding clutch mounted on the shaft, and fitted for movement, as shown most clearly in Fig. 5, for connection to and disconnection 65 from cam *l*.

m' is a lever, hung on the under side of tank *A*, for moving the clutch, whereby when the clutch is moved to engage the cam the latter is rotated by the shaft and the pan *h* raised 70 and lowered once at each revolution of the shaft. Lever *i* has a number of holes at varying distances from the fulcrum, so that the pin connecting rod *k* to the lever can be set in and out to vary the throw or movement of the pan. 75 These parts constitute the mechanism for carrying the paper through the tank and wetting it. The feed and delivery mechanism is as follows:

n is a table fixed on the upper ends of standards *a*, for holding the stock of paper. 80

o is an inclined table fixed on one side of tank *A*, in front of rollers *b b*.

n' are side gages, adjustable on table *o*, for 85 guiding the paper.

p p are feed-fingers projecting through slots in table *o* from a rock-shaft, *o'*, which is mounted in bearings beneath the table.

p' is a crank-arm on shaft *o'*.

q is a pivoted arm at the side of the machine, hung on the upper end of a rod, *r*, that is fitted to slide vertically in a guide, *r'*, and is further held in place by its lower end striding the main shaft *e*. 90

q is a rod connecting the crank-arm *p'* and 95 arm *q'*.

s is a cam on shaft *e*, arranged to act on a pin, *s'*, projecting from rod *r*, so as to raise and hold up the rod for a time at each revolution of the shaft. 100

t is a cam or projection on shaft of upper roller *b*, for taking against the upper end of arm *q'*, or against a projection therefrom, for the purpose of moving the arm, and with it 5 the fingers *p*, by the connections described. Both arms *p' q'*, connected by rod *q*, have several holes to allow adjustment of the pin connecting rod *q*, so as to vary the extent of movement, and the rod is made in two pieces connected by a turn-buckle, *q''*, so that the parts may be properly positioned.

At the opposite end of tank *A* is fixed a guard of curved wires, *u*, extending down from the delivery-point of roller *c*, and a rock- 15 shaft, *u'*, extending transversely above the wires *u*, carries curved arms *v*, which in their normal position lie close to the fixed wires, with space between for the paper to enter. A rod, *v'*, connects an arm, *v*, on shaft *u'* to 20 the pivoted arm *q'*, so that the shaft is rocked simultaneously with the movement of feed-fingers *p*, and the arms *v* thus swung out as the fingers *p* move inward. The rollers *c* are grooved to receive the fixed guards *d'*, which 25 are placed at intervals in the length of the rollers, to prevent the wet paper from adhering to and winding on the rollers. At the delivery end, beneath guards *u*, is a table, *a'*, supported at its ends by slide-racks *b'*, that 30 engage cogged segments on the ends of weighted levers *e'*, so that the table is held up close to the guards when empty, and descends as the weight of paper increases on it, thus preventing disarrangement of the sheets by a fall 35 to any distance. The main shaft *e* is to be rotated by connection to a prime mover.

In operation, a quire of paper is laid on table *o*, in front of fingers *p*. The fingers then moving forward, the forward edge of the 40 paper is thereby pushed between rollers *b*, and the paper is carried beneath roller *f* by cords *g*. At the same time the pan *h* rising and being held up until the paper has passed, the water is brought into contact with the paper to-wet the under sheets only, or to submerge the whole, according to the adjustment. The paper, continuing to move by the 45 cord, is carried out by rollers *c*, and as soon as the whole is received between the fixed 50 guards *u* and arms *v* the latter swing out and the paper drops upon the table. At the same moment another quire is moved forward by feed-fingers *p*. The delivery-rolls *c* squeeze the surplus water from the paper passing between them.

In case it is required to wet only alternate quires or lots, the lever *m'* will be moved to disengage clutch *m* from cam *l*, so that the pan *h* will not be raised to wet the paper 55 passing through, and the clutch engaged

again for the next lot, and so on, thereby causing the deposit on the table *a'* of dry paper between every two wet quires.

It will be seen that the extent of the wetting is entirely under control of the operator. The 65 machine will operate rapidly, the paper passing through almost continuously.

I do not limit myself to the details of construction exactly as described. The connections may be arranged as found most desirable, and the delivery-fingers are to be made adjustable to suit different sizes of paper. 70

Having thus fully described my invention, I claim as new and desire to secure by Letters Patent—

1. In paper-wetting machines, the combination, with water-tank *A* and endless cords or belts for carrying the paper, of the pan *h*, arranged for movement to and from the belts, substantially as shown and described. 75

2. In paper-wetting machines, the combination of rollers *b b c e*, belts *g*, guide-roll *f*, and pan *h*, fitted for movement to and from the guide-roll, substantially as described.

3. In paper-wetting machines, the pan *h* 85 and lever *i*, combined with tank *A* and the paper-carrying cords, substantially as shown and described.

4. In paper-wetting machines, the combination of water-pan *h*, lever *i*, rod *k*, cam *l*, 90 and shaft *e*, substantially as described, for operation as specified.

5. The combination, with the lever *i*, carrying the bottom valved pan, *h*, of the slotted rod *k*, having pin *l'*, the shaft *e*, carrying loose 95 cam *l*, and the clutch mechanism *m m'*, whereby the pan may be raised or lowered, as described.

6. The combination, with feed-rolls *b b*, of which the upper one carries a cam, *t*, on its 100 shaft, of the inclined slotted table *o*, the side gages, *n'*, the rock-shaft *o'*, having crank-arm *p'* and feed-fingers *p*, the slide-rod *r*, having pin *s'* and pivoted arm *q'*, the rod *q*, connecting the arms *p' q'*, and the shaft *e*, having cam 105 *s*, as and for the purpose specified.

7. The combination, with the rolls *c c*, of the fixed curved guard-wires *u*, the transverse rock-shaft *u'*, carrying curved arm *v*, the slide-rod *r*, having pivoted arm *q'*, and the rod *v'*, 110 connecting arms *q' w*, as and for the purpose specified.

8. In paper-wetting machines, the combination, with delivery-rollers, of guards *u* and vibrating arms *v*, substantially as shown and 115 described.

JOHN WESLEY MORRISON.
